UNITED STATES PATENT OFFICE.

HARRY D. BINKS, OF OAK PARK, ILLINOIS, ASSIGNOR TO BINKS SPRAY EQUIPMENT CO., OF CHICAGO, ILLINOIS, A CORPORATION OF ILLINOIS.

GANG SPRAY.

Application filed November 7, 1925. Serial No. 67,514.

My invention relates to spraying means for applying a uniform coating to large surfaces, such as sheets or panels.

In varnishing linoleum so as to give the rather porous constituents of the body of the linoleum a waterproof coating, it is highly important that every portion of the face of the linoleum should be adequately coated with the varnish. It is likewise important that this varnish should be applied with an equal thickness, as any differences in the transparency of the coating would mar the appearance of the colored pattern of the linoleum.

Heretofore, it has been customary to apply such a protective coating to wide flat surfaces by using a manually held spraying appliance which is moved to and fro while adjacent to the surface which is to be coated.

Such a manipulation, although commercially satisfactory for the coating of products in which variations in the transparency of the applied coating are not material, or in which this coating is opaque, has not been entirely satisfactory in the varnishing of linoleum. In practice, even an experienced operator is apt to leave occasional spots insufficiently coated, while other portions will receive such an unduly heavy coating as to interfere with the uniformity of the varnish and to dim portions of the finished product.

Moreover, streakiness commonly occurs at the junctures of the comparatively narrow bands in which the coating is successively applied, it being impossible to project a single and substantially uniform spray which exceeds more than a small fraction of an ordinary piece of linoleum in width. Furthermore, the cost of applying a coating in this manner is undesirably high, owing both to the necessity of employing of expert workmen for this purpose and to the relatively slow rate at which the coating can be applied with a single spraying appliance.

A further difficulty commonly encountered in the applying of coatings to linoleums, veneer panels or the like, lies in the inability of maintaining a spray of uniform consistency in the ordinary spraying appliance, owing to the readiness with which the coating material will clog the relatively

small channels and ports in such appliances.

My present invention aims to overcome all of these objections by providing a spraying appliance which will simultaneously project the coating material in a series of finely divided sprays over the entire width of the object which is to be coated, which will effect the needed subdivision of the coating liquid into a spray without requiring the liquid to pass through any small passages or ports, which will permit the density of the spray to be varied simultaneously and equally at all of the spray outlets, and which will permit the thickness of the applied coating to be varied also by varying the rate at which the linoleum sheet, panel or other object is moved through the field of the spray.

Furthermore, my invention provides exceedingly simple and easily manipulated means for supplying the liquid simultaneously and uniformly to all of the spray outlets, and provides an arrangement which will readily permit a cleaning of these outlets or a removal from them of dried coating material.

Still further and also more detailed objects will appear from the following specification and from the accompanying drawings, in which

Fig. 1 is a front elevation of a gang spray appliance embodying my invention.

Fig. 2 is a fragmentary plan view of the same, taken from the line 2—2 of Fig. 3.

Fig. 3 is a transverse section taken along the line 3—3 of Fig. 1, showing also a portion of a liquid supply tank, together with the connection between this tank and the trough of my gang spray, the trough being tilted as it appears when this gang spray is in operation.

Fig. 4 is an enlarged section similar to a portion of Fig. 3, showing the relative positions of one of the air projecting nozzles, the spray nozzle casing, and the level of the liquid when my gang spray appliance is in operation.

Fig. 5 is a fragmentary elevation of a part of the gang spray embodying my invention, showing this as provided with a semi-cylindrical spray nozzle casing in place of the

corresponding tubular casing of Figs. 1 to 4 inclusive.

Fig. 6 is a section taken transversely through Fig. 5 along the line 6—6.

Fig. 7 is an enlarged perspective view of one of the spray nozzle casings employed in Figs. 5 and 6.

Fig. 8 is a fragmentary front elevation of another embodiment of my invention, namely one employing a flat plate as a spout for a spray nozzle casing.

Fig. 9 is a section taken through Fig. 8 along the line 9—9 of that figure.

Referring first to the embodiments of Figs. 1 to 4 inclusive, these show a liquid supply tank 1 connected by a flexible tube 2 to a trough 3, the supply connection being controlled by a stop cock 4. The trough 3 is supported by a pair of alined shafts projecting from opposite ends of the trough and each journaled in a hanger 6, one of these shafts having fastened to it a hand wheel 7 by means of which the trough can be tilted as desired.

Rigidly mounted with respect to the trough are a series of air projecting nozzles 8, each of which is here shown as connected by a riser pipe 9 to an air supply pipe 10. Compressed air is supplied to the pipe 10 by pipes 11 which are connected to the aforesaid pipes by swiveling elbows 12 so as to maintain an uninterrupted air supply connection regardless of the movement which is imparted to the pipe 10 when the trough is tilted. Each of the air projecting nozzles 8 is maintained in rigid position with respect to the trough, as for example by a strap 13 connecting the corresponding riser pipe 9 with the back of the trough, and each of these nozzles has in front of it a suitable arrangement for discharging paint or other liquid 14 from the trough and for cooperating with the jet of air through the nozzle in projecting the liquid in a finely divided spray. For this purpose, Fig. 4 shows the front wall of the trough 3 as provided in front of each of the air nozzles 8 with a notch 15 through which a tubular discharge outlet or nozzle casing 16 extends in axial alinement with the air nozzle 8.

Each such discharge outlet desirably is mounted so that it can be manually detached from the trough to permit the removal of any liquid which has dried on the bore of the said outlet, for which purpose Figs. 1 to 4 show each outlet 16 as carrying a pair of semi-annular flanges of angle-shaped axial section so as to afford a pair of webs respectively engaging the inner and outer faces of the front wall 3^A of the trough adjacent to one of the said notches. Moreover, the discharge outlets 16 and the air jet nozzles 8 behind them are uniformly spaced longitudinally of the trough and all have

their axes in a common plane, which plane is horizontal when the appliance is not in use as shown in Fig. 1.

In using such a gang spray appliance, the trough or liquid container is tilted forwardly (as shown in Fig. 4) to such an extent that the varnish or other liquid in the trough will flow in a thin stream through the bottom of the bore of each nozzle casing 16. When this is done with air under pressure issuing from the air nozzle 8, the outlet 16 acts after the usual manner of a spray nozzle casing in producing a whirling action within this casing so as to project a spray 18 consisting of finely divided liquid particles. By suitably proportioning the diameter and length of the outlet 16 to the outlet bore of the air nozzle 8 and suitably spacing the latter with respect to the outlet 16, I can readily produce a substantially conical spray in which the projected liquid particles are distributed with a fair uniformity, and with a divergence of the spray which will cause the sprays 18 from the adjacent spray nozzles to just reach each other by the time that the spray reaches the linoleum or other flat object 19 which is to be coated.

This object is fed by any suitable means and at a uniform rate through the field of spraying of all of the said nozzles. For this purpose, Fig. 1 shows the sheet of linoleum 19 as slid over a table 20 by friction rollers 21 mounted on a single rotating shaft 22, any suitable means being employed for rotating this shaft at such a speed as will cause the linoleum to receive a coating of the desired thickness while passing through the field of the spray. This thickness of the coating can also be adjusted by varying the tilting of the trough, and differences in this tilting will likewise allow the user to compensate for differences in the viscosity of the liquid employed.

By using a simple tube (or trough-like bottom portion of a tube) as the nozzle of each of the spraying appliances mounted on my trough and causing the liquid to flow direct by gravity into the bottom of this tube, I avoid the need of the small passages or ports commonly employed in the spraying appliances as heretofore in use. Consequently, I avoid the clogging of these spray appliances when my apparatus is in use and hence can readily secure that uniformity of the spray from all of the spray nozzle casings which is needed for insuring a uniformity of the applied coating. So also, since the tilting of the trough affects all of the outlets uniformly, I can readily vary the density of the spray equally at all of the spray outlets. When the use of my apparatus is discontinued, the trough is tilted back to its normal position of Fig. 1, after which each of the spray nozzle casings or

discharge outlets can be lifted out of its interlocking engagement with the front of the trough, so as to permit the said outlet to be scraped clean or to be rinsed out with a suitable solvent for the liquid.

However, while I have heretofore described my gang spray appliance as including a tubular spray-producing casing, I do not wish to be limited to this shape for the spray outlet, as various other forms might be employed with substantially equal facility. For example, Figs. 5, 6 and 7 show portions of a gang spray appliance in which the spray-producing casing consists of a semi-cylinder 19 corresponding to the lower half of the tube 12 in Fig. 4 and similarly secured to a pair of angle sectioned flanges 17 which serve for supporting it on the front wall 3^A of the trough.

Figs. 8 and 9 show an allied arrangement in which the spray-producing member consists of a flat plate 20 having its upper face in an axial plane medial of the adjacent air projecting nozzle 8. With this form, the rear end of the plate 20 may be bent downward to afford a flange 31 engaging the rear of the trough front 3^A, while an angle bracket 22 is secured to the bottom of the plate 20 and engages the forward face of the trough front.

In each of the embodiments above described, it will be obvious that the level of the liquid in the trough can readily be controlled by a simple manipulation of the stop cock 4. The rate of flow of liquid into the spray nozzle casing can be controlled in the embodiments of Figs. 1 to 9 by varying the inclination of the trough, and in all cases the thickness of the applied coating can be varied by correspondingly varying the rate at which the object sheet 19 moves through the field of the spray. Since all of these adjustments are easily made and since the spray-producing portions of my appliance cannot readily clog or vary the fineness of the resulting spray, my appliance can readily be operated for long periods without requiring any attention other than the maintaining of the supply of liquid in the tank 1 and the proper feeding of the linoleum or other object sheets. However, while I have illustrated and described certain desirable features of construction and arrangement, I do not wish to be limited as to these, since many changes might obviously be made without departing either from the spirit of my invention or from the appended claims.

I claim as my invention:—

1. The combination with a container and liquid therein, of a plurality of spraying appliances operatively connected to the liquid, the said appliances being arranged for projecting sprays along parallel axes, and means for simultaneously moving the container and the said appliances so as to

control the supply of liquid from the container to the said appliances.

2. A gang spray appliance including a horizontal trough, a supply of liquid connected to the trough, a plurality of spray appliances carried by the trough and uniformly spaced along a longitudinal wall of the trough and having parallel axes extending at right angles to the said wall, air supply ducts carried by the trough for supplying compressed air to all of the spray appliances, and means for tilting the trough about a horizontal axis parallel to the said wall.

3. In a spraying appliance, a horizontal liquid-containing trough, a plurality of spray appliances uniformly spaced longitudinally of the trough along the front wall of the trough, means for supplying air uniformly to all of the said appliances, a pair of shafts carried respectively by the ends of the trough and having aligned horizontal axes parallel to the said front wall, supports in which the shafts are respectively journaled, and means associated with one of the shafts for rotating the latter to rock the trough about its said journaled supporting.

4. In an apparatus for coating an object with a liquid, a trough containing the liquid, a plurality of axially parallel trough-shaped outlets mounted on the trough, air jets respectively behind and in substantially axial alignment with the said outlets, and means independent of the air jets for varying the level of the liquid in the trough with respect to the inner ends of the said outlets.

5. In an apparatus for coating an object with a liquid, a container for the liquid, a plurality of axially parallel outlets mounted on and projecting from the container and arranged to have liquid from the container flow directly into them, air jets respectively behind the said outlets, and means for tilting the container to vary the flow of liquid into the said outlets.

6. In an apparatus for coating an object with a liquid, a container for the liquid, a plurality of axially parallel outlets mounted on the container and arranged to have liquid from the container flow through them, air jets respectively behind and in axial alignment with the said outlets, and means independent of the air issuing from the said jets for varying the level of the liquid in the container with respect to the said outlets.

7. In an apparatus for coating an object with a liquid, an upwardly open container for the liquid, a plurality of trough-shaped outlets of upwardly concave transverse section spaced along the top of a wall of the container and having parallel axes disposed in a common plane and all arranged to have liquid from the container flow direct from the trough through the said outlets, air jets respectively behind and axially aligned with

the said outlets, and means for varying the level of the liquid in the container with respect to the said outlets.

8. An apparatus as per claim 7, in which each of the said outlets is detachably mounted on the said wall.

9. An apparatus as per claim 7, in which the said trough wall has notches through which the said outlets respectively extend.

10. 10. A liquid spraying apparatus, comprising a horizontal liquid-containing trough having a longitudinal front wall and mounted for rotational movement about an axis longitudinal of the trough, a plurality of outlets mounted at the said front wall and disposed for having liquid flow directly into all of them from the trough, and means for rotating the trough about its said axis to vary the rate at which liquid flows from the trough into all of the said outlets and means fast with respect to the trough for projecting air longitudinally of the several outlets and into engagement with liquid flowing from the trough through the said outlets.

11. A gang spray comprising a horizontal liquid-containing container having a longitudinal front wall, a plurality of spray appliances mounted at and extending transverse of the said front wall and disposed for having liquid flow into all of them direct from the container, and means for tilting the container about a horizontal axis parallel to the said front wall so as to vary the rate at which liquid flows from the container into the said appliances.

12. Spraying means comprising a horizontal liquid-containing container having a longitudinal front wall, a plurality of liquid discharge outlets of upwardly concave arcuate section supported by and extending across the said wall and spaced uniformly along the latter and having their axes in a common plane, air projecting nozzles respectively behind and in axial alinement with the said outlets and supported independently of the said outlets, and means for

tilting the container about a horizontal axis parallel to the said front wall so as to cause liquid to flow from the container simultaneously through all of the said casings.

13. Spraying means comprising a horizontal liquid-containing trough having a longitudinal front wall, a plurality of discharge outlets, detachably supported on the upper edge of the said wall and spaced uniformly along the latter and having their axes in a common plane, a corresponding number of air projecting nozzles supported independently of the said outlets and respectively disposed behind and in axial alinement with the said outlets, and means for tilting the trough about a horizontal axis parallel to the said front wall so as to cause liquid to flow from the trough simultaneously into all of the said outlets, each of the said outlets having a pair of flanges respectively engaging the front and rear faces of the said front wall for securing the outlet to the said wall.

14. The combination with a container, of liquid within the same, an outlet fast upon a wall of the container and spaced from the bottom of the container, the outlet having a trough-like bottom portion extending transversely of the said wall, means for raising the level of the liquid in the container with respect to the inner end of the outlet to cause liquid to flow out over the said trough-like bottom portion, and means for projecting air against the liquid flowing over the said bottom portion for projecting the liquid outwardly of the container in the form of a spray.

15. In a spraying appliance, an air jet nozzle, a spray producing member disposed forwardly of the nozzle and extending parallel to the said nozzle, the said member having a trough-shaped bottom; and means for causing liquid to flow from the rear of the said member along the said bottom.

Signed at Chicago, Illinois, November 4, 1925.

HARRY D. BINKS.
